UNITED STATES PATENT OFFICE.

WALTER S. MINOR, OF CUNNINGHAM, TENNESSEE.

STAVE JOINTER.

Application filed August 2, 1924. Serial No. 729,805.

To all whom it may concern:

Be it known that I, WALTER S. MINOR, a citizen of the United States, residing at Cunningham, in the county of Montgomery and State of Tennessee, have invented certain new and useful Improvements in Stave Jointers, of which the following is a specification, reference being had to the accompanying drawings.

10 This invention relates to automatic stave jointers for jointing barrel staves, and more particularly to certain improvements in the stave jointing machine illustrated and described in my Patent #1,229,307, granted

15 June 12, 1917.

One of the objects of the present invention is to provide improved means for supporting the jointing saws, which saws are so mounted that both the saws are relatively 20 movable toward or from each other and both saws are disposed in planes which converge toward the center of motion of the mandrel supporting frames.

A further object is to provide improved 25 means whereby both saws may be simultaneously shifted toward or from each other, and provide in this connection automatic means whereby the distance between the saws may be gradually increased and then 30 gradually decreased to form the bilge in the stave, that is to increase the width of the stave at the middle thereof, the side edges of the stave always being kept at the proper angle with relation to each other to form 35 the completed barrel.

A still further object is to provide a mechanism of this character which is so constructed that either wide or narrow staves may be jointed, the angle of the side edges 40 of the staves being automatically kept true, and in this connection to provide saws which are in radial alignment with the hinge pins upon which the mandrel frames are supported so that though the angle of bevel 45 in the staves when jointed will be different for each and every width, yet all will center at the center of the completed cask.

Another object is to provide a sliding feed table having a guide rail operatively 50 connected thereto on one side and having a straight edge indicator for the right hand saw.

Still another object is to provide means 55 whereby the feed table has transverse movement simultaneously with the left hand saw and whereby the straight edge has transverse

movement simultaneously with the right hand saw.

A further object is to provide a construction of this kind with a template which controls the inward and outward movement of the saws, that is the movement toward or from each other, whereby to give proper curvature automatically to the side edges of the completed stave.

A still further object is to provide automatic means for longitudinally shifting the template or reciprocating the same as soon as the board from which the stave is to be cut is in position to be engaged by the saws 70 and to cause the automatic disconnection of the template from its operating means when the stave has been fully cut.

Another object is to provide in a machine of this character a circular saw with 75 just enough of the saw projecting above the stave rest to cut through the stave to thus prevent imposing an undue strain upon the saw.

Still another object is to provide a stave 80 jointer in which the form of the joint on the finished stave is controlled by the form of cam or template used, making it an easy matter to change from one to another.

A still further object is to provide means 85 whereby the saws may be manually adjusted toward or from each other, the feed table with its guide and straight edge opposed to the guide simultaneously adjusted toward each other by the same means, and provide means whereby the saws may be automatically shifted toward or from each other 90 after having been manually adjusted.

Another object is to provide means for 95 shifting the saws which includes a double armed crank and a shaft upon which the crank is mounted, each arm being connected to one of the pivoted saw supporting members, the shaft being rotatively adjustable by hand whereby to shift the crank and the saws, and provide automatic operating means for shifting the saws toward or from each other a predetermined amount which includes an arm loosely mounted upon the shaft, and a clutch whereby the arm may be engaged with the shaft for rotative movement therewith in all rotated positions of the shaft.

Other objects will appear in the course of the following description.

My invention is illustrated in the accompanying drawings, wherein:

Figure 1 is a longitudinal sectional view of a stave jointer constructed in accordance with my invention;

Figure 2 is a top plan view partly in section of the construction illustrated in Figure 1;

Figure 3 is an elevation of the jointer shown in Figure 1;

Figure 4 is a section on the line 4—4 of Figure 1;

Figure 5 is a detail elevation of the shaft 29, the levers 33 and 36, and the clutch connection, the view being partly in section;

Figure 6 is an elevation of the structure shown in Figure 5;

Figure 7 is a fragmentary section on the line 7—7 of Figure 2;

Figure 8 is an elevation of part of the frame of the machine and the mechanism 20 for operating the tank shaft 101;

Figure 9 is a fragmentary section on the line 9—9 of Figure 8;

Figure 10 is a diagrammatic perspective view of the saw supporting frames and the 25 saw table and straight edge, showing the manner in which the latter are connected up with the saw supporting frames;

Figure 11 is a side elevation of one of the 30 beams 19, the supporting bracket being in section.

Referring to these drawings, it will be seen that my improved jointer including a supporting frame comprises the transverse members 10, the longitudinally extending 35 members 11 which constitute the base of the machine, the uprights 12, and the transverse braces 13. Obviously I do not wish to be limited to this particular form of base.

Extending upward from one of the longitudinal beams 11 at what will be termed 40 the rear of the machine and projecting above the upper ends of the vertical members 12 is a post 14. Generally speaking, the framework composed of the members 10, 11, 12 45 and 13 supports a laterally reciprocating saw table and two saws. Mounted at the forward end of the table are two opposed mandrel supporting frames 15 and 16. Each of these mandrel supporting frames is somewhat 50 arcuate in form and the lower end of each mandrel supporting frame is rigidly mounted upon an oscillating bar 17 pivotally supported by pins engaging brackets 17^a, the pivots for each of these mandrel supports being in line with each other. The 55 two supports 15 and 16 are practically opposed to each other and almost in the same plane, and each mandrel support at its inner end adjacent its pivot has an upright 18.

60 Mounted on these uprights and on the frames 15 and 16 are the bearings 19, and mounted in these bearings are the mandrels 20 and 21, each carrying at its inner end a circular saw 22. The circular saws 22, it 65 will be seen, are normally at an angle to each

other and are so angularly related that the plane of each saw will intersect the pivotal axis of the supports 15 and 16 under all circumstances of operation (see Figure 4). Each pair of bearings 19 is mounted upon a base 23 which rests upon brackets 24, and these bearings are adjustable by means of screws 25. Each mandrel carries upon its outer end the belt pulley 26 whereby the 70 saws may be driven.

Mounted in a bearing 27 carried by the post 14 and in a bearing carried by a post 28 is a rock shaft 29 having at the end remote from the saw mandrels the hand lever 30 whereby the shaft may be rocked. This rock 80 shaft also carries upon it an arm 31 having a counter-balancing weight 32 which tends to bring the rock shaft back to normal. Mounted upon the rock shaft and rockingly therewith is a two-armed lever 33 connected by links 34 and 35 with the supports 15 and 16 respectively. Thus it will be obvious that when the rock shaft 29 is shifted in a counter-clockwise direction, the free ends of the supports 15 and 16 will be shifted away 90 from each other and thus the saws will be shifted away from each other, and that if the rock shaft be shifted in a clockwise direction beyond what may be termed its normal position, the free ends of the supports 15 and 16 will be forced toward each other. Thus by shifting the rock shaft, the angle of the saws relative to each other may be changed.

This rock shaft carries loose upon it the 100 downwardly extending arm 36, the upper end of which is angularly extended and normally engaged with the rock shaft for movement so that as the rock shaft oscillates, the lower end of the arm 36 will shift 105 transversely. The lower end of this arm carries upon it a roller 37 which bears against a template or cam, as will be later described. The arm 36 is drawn inward to cause this roller to bear against the cam by 110 means of a contractile spring 38. Mounted upon the shaft 29 is an arm 39 which carries upon it what may be termed a clutch 40 which is attached to the arm 39 in any suitable manner. One end of this clutch 40 is angularly extended, as at 41, and pivoted to the opposite end of the clutch is an arcuate lever 42, one end of which carries a set screw 43, the opposite end of the lever being connected by a link 44 to a trigger 115 lever 45 which is pivoted upon a bracket 46 projecting from the lever 30. This trip lever or trigger lever projects up above the member 40 for a purpose which will be later stated.

Mounted upon the member 36 is a curved rod or quadrant 47 which extends between the end of the arm 39 and the prolongation 41 of the clutch member 40. A spring 48 bears at one end against the arm 39 and at 120 125 130

the other bears against the lever 42 and urges the upper end of the lever outward, thus urging the screw 43 through the member 39 and against the quadrant 47.

5 Mounted upon a shaft 49 carried by the uprights 36 is a pulley 50 from which power is transmitted to the machine, and also mounted upon this shaft 49 is a pulley 51 from which the feeding mechanism is 10 driven. Mounted in suitable bearings in the supporting frame in front of the saws is a feed roller 52, and mounted in suitable bearings upon the supporting frame on the other side of the pair of saws is a feed roller 53. 15 These rollers are mounted upon shafts 54 and 55 respectively, both of these shafts carrying pulleys 56. The belt 51^a passes down over the rearmost pulley 56, then up over an idler pulley 57 which is suitably 20 supported upon the frame, then downward and around the inner pulley 56 and up to the pulley 51, and so back again.

Operatively supported in bearings above each of the feed rollers 52 and 53 are the 25 idler rollers 58 mounted in vertically slotted bearings and urged downward by means of springs 59 supported in suitable housings. Extending transversely across the frame forward and rearward of the saws and near 30 the upper portions of the saws are the supporting bars 60, and mounted upon these supporting bars for transverse sliding movement are the stave supports 61. These stave supports are controlled by vertical members 35 62 which are carried by the upwardly extending members 18 (see Figure 10) and by the members 63 which are mounted upon the longitudinal members 17. An idler roller 64 is mounted at the rear end of the 40 machine in suitable brackets and is, of course, on a level with the rollers 52 and 53.

It will be noted that the stave supports 61 intersect the saw near the upper portion of the saw so that just enough of the saw 45 extends above the stave rests or supports 61 to cut through the stave. Pivotally mounted upon a downwardly extending bracket 65 is a trip lever 66, the rear end of which is turned upward in a curve, the 50 upper extremity of this curved portion projecting slightly above the upper faces of the stave rests 61 and being beveled downward and rearward, as at 67. When a stave passes over the roller 52, it strikes the upper 55 end of this trip lever at the beveled portion 67 and forces the trip lever downward, raising the rear end thereof. Pivot to this rear end is the depending link 68.

A feed table 69 is secured to cross bars 60 and 71 which have sliding movement in suitable longitudinally extending supports 72 under the upper frame member 73. Mounted upon the feed table is a guide rail 74, this guide rail being hinged under the 65 table by rods 75 (see Figure 2). An arm

76 is attached to this guide rail and is counterweighted so as to urge the guide rail into a position parallel to and extending upward above the upper face of the table 69. Operatively associated with the feed 70 table is the straight edge or gauge 77 which is carried by two outwardly projecting arms 78 which extend through a rock shaft 79. These arms are mounted in the rock shaft so as to shift transversely through the rock 75 shaft and are held in adjusted positions by means of nuts 80 engaging the arms 78 on each side of the rock shaft.

The gauge 77 is adapted to be depressed 80 into proximity to the face of the plank lying upon the table 69 and by its use the operator is enabled to judge just how much of the plank, which is simply rough edged, can be utilized in forming the stave. This straight edge 77, as will hereafter appear, 85 is adjustable toward or from the middle line of the machine, as is the gauge 74, and the table 69, and as the table 69 and the gauge or straight edge 77 are shifted toward the middle line of the machine the saws are also 90 shifted toward the middle line, and when the tables 69 and the gauge 77 are shifted away from this middle line the saws are likewise shifted and to a corresponding degree. 95

This rock shaft 79 carries an arm 81 connected by a link 82 to one arm 83 of a bell crank lever 84 mounted upon a bracket 85 attached to the post 14. The short arm of the bell crank lever 84 is connected to a 100 link 86, which in turn is pivoted to the upper end of the hand lever 45, as at 87. Thus it will be obvious that when the hand lever 45 is drawn inward toward the lever 30, the upper end of this lever 45 will be shifted 105 forward. This will turn the bell crank 84, lift up on the link 82, and rock the shaft 79 so as to carry the straight edge 77 downward against the feed table. As soon, however, as the hand is released on the lever 45, the 110 straight edge will be carried upward.

The rock shaft 79 is mounted at its ends in downwardly extending legs 88, which at their lower ends are mounted in a rock shaft 89 carried in the supports 12. The feed 115 table 69 has extending from it the horizontal rods 90 which are connected to the upper ends of arms 91, which in turn are mounted upon a rock shaft 92. Mounted upon the member 17 of the right hand mandrel support 16 is an upwardly extending arm 93, which at its upper end is connected by a link 94 to one of the arms 88. A like arm 95 extends upward from the member 17 of the left hand mandrel support and is connected at its upper end by means of a link 96 to an arm 97, in turn connected to the rock shaft 92. Thus it will be obvious that the feed table 69 moves laterally with the 120 left hand mandrel support 15, while the 125 130

straight edge is so connected to the right hand mandrel support 16 that they move together.

Mounted in guides 98 supported in any suitable manner on a longitudinally extending beam 78^a (see Figure 2), is a template or reciprocating cam 99, the outer edge face of which at one point is outwardly curved, as at 100, in conformity with the curvature given to the middle of a barrel stave. Operating against this cam is the roller 37 carried by the arm 36 previously referred to. The cam or template is reciprocated through the guides 98 by means of a crank shaft 101 supported in bearings carried by the uprights of the base frame, said shaft having thereon a crank arm 102 with a pitman 103 which operatively connects and is pivoted to one end of the template 99. Thus as a complete rotation is given to the shaft 101, the template 99 will be given a full stroke to the left in Figure 2 and then a full stroke back again so that the roller 37 will be shifted outward to its full extent and then shifted inward again. This intermittent rotation of the shaft 101 is secured by a clutch mechanism, as will be now described:

Mounted loosely upon the crank shaft 101 is a gear wheel 104, which in turn is engaged by a pinion 105 mounted upon the shaft 54. This pinion 105 meshes with the gear wheel 104, and carried by this gear wheel 104 to rotate with it is a ratchet toothed gear wheel 106 which is also loose upon the crank shaft 101. Mounted upon the shaft 101 to rotate therewith is an arm 107, and pivoted upon the extremity of the arm 107 is a pawl 108, one end of which is provided with an inwardly projecting tooth 109, while the outer end is provided with the outwardly projecting tooth 110 having a beveled face. Co-acting with this tooth is a latch 111 which forms the upwardly projecting arm of a bell crank lever 112, the other end of this bell crank lever being connected by the link 68 to the trip lever 66.

Thus it will be obvious that when a stave is passed between the rollers 52 and 58 and strikes the beveled end 67 of the trip lever 66 that this beveled end will be depressed, lifting upward on the rod 68, which in turn will pull upward on the arm 112 of the bell crank lever and shift the upwardly extending arm 111 out from beneath the tooth 110. As soon as this has been accomplished, the spring 114 which is connected between the arm 107 and the pawl 108 will pull the pawl 108 inward until the tooth 109 engages a tooth on the wheel 106, when rotation of the pinion 105 will be transmitted to shaft 101 through the gear wheels 104 and 106, so that just as soon as a stave reaches the spot where it is about to be sawed it will automatically start the template 99 moving and this will continue through one complete rotation of

the wheel 106 and until the stave has passed the trip lever 66 and the parts are again in the position shown in Figure 9, when the tooth 110 will catch against the latch 111.

In the operation of this mechanism, the unjointed stave, if with one sawed edge, is placed on the feed table 69 with the sawed edge against the guide 74. The operator then draws lever 45 against the handle 30 and thence through the link 44 releases the clutch 40. At the same time this brings the straight edge 77 down on the top of the stave. The operator then shifts the lever 30 to the right or left until the straight edge shows the limit of available timber. When the grip on the lever 30 is released and grip on the member 45 is also released, the spring 48 locks the rock shaft 29 to the vertical bar 36. When the handle 45 is released and the spring 48 forces the lower end of the lever 42 inward, gripping the sector-shaped member 47 which is attached to the member 36, thus locking the member 36 to the shaft 29 and locking this arm 36 to the arm 39 at a predetermined angle. At the time that the handle 45 is released, the spring 48, through the link 44, forces the upper end of the lever or member 45 outward. This pulls on the link 86 and bell crank with its arms 84 and 84 lift on the link 82 and through the arm 81 rotates the rock shaft 79 and this, of course, causes the raising of the straight edge 77, thus freeing the stave, which is then pushed forward into the feed rollers, and when the stave reaches the end 67 of the trip lever 66, it presses this free end downward and throws the latch 111 out from beneath the teeth 110. The pawl 108 then springs into engagement with the wheel 106 and this operatively connects the cam or pattern 99 with the cam or pattern feeding means and advances the pattern one stroke to the left and then the pattern moves a stroke to the right back to its initial position. In other words, the cam or pattern makes one complete reciprocation before it is again released from its operating means.

This pattern or template 99, through the action of the roller 37 and the arm 36, oscillates the shaft 29 and throws the arms 33 in one direction or the other so as to shift the saws further apart upon the stroke of the cam or pattern in one direction and then shifts the saws nearer together upon a movement of the pattern or cam in the other direction. When the cam or template has moved a full stroke forward, one-half of the stave has been jointed or cut and the cam has moved the vertical bar 36 at this lower end outward and the double crank 33 by the connecting rods 34 and 35 have moved the saws outwardly, increasing the width of the stave at this point, and as the rest of the stave passes the saws, the return of the cam or template allows the saws to return to the

first position, which makes this half of the stave an exact duplicate of the first half, that is the two ends have the same width with slightly curved sides, with the maximum width in the center of the same. Just as the stave passes out of the saws, the cam or pattern reaches its first position and the latch 111 forces the pawl 108 out of engagement with the ratchet wheel, thus stopping 10 the action of the crank shaft and stopping the action of the cam or template.

My machine is particularly advantageous over the machine shown in my prior patent by reason of the fact that I secure increased 15 capacity, that there are fewer parts to the machine itself, and the machine is much more simple. Furthermore, it entirely eliminates waste of material. A slab wide enough for two staves or one with two rough 20 edges is placed on top of the guide rail 74 which drops to the level of the feed table and returns to place when the stave leaves the table. The cam or template 99 imparts the same movement to the rock shaft 29 for 25 each and every width of stave, but when the spacing lever 30 is shifted from a position for a wide stave to the position for a narrow stave, the position of the double crank 33 is such that the arms of the double crank ex- 30 tend nearly horizontally and, therefore, a rocking movement of a certain amplitude given to the shaft 29 will only cause a relatively slight transverse movement of the saws, making a less bilge in the relatively 35 narrow stave. The arrangement is such as to give to each stave its proportion of the total bulge of the cask so that the completed cask is uniform whether wide or narrow staves are used.

40 It will be noted that the double crank 33 and shaft 29 are adjustable with reference to the saw controlling arm 36 by means of the lever 30 and that the straight edge or guide 77 is connected through arm 93, link 45 94 and arm 88 with one of the oscillating bars 17 which support a saw mandrel. Thus the rotation of shaft 29 by means of handle 30 shifts the saws nearer to or further from each other and the shifting of the saws sets 50 the straight edge 77 and the guide 74 (because this guide is mounted on the laterally shifting table 69) nearer to or further from each other. Thus if the handle 30 is moved the saws are shifted and the table with guide 55 74 and the straight edge 77 are moved so that the operator can, by noting the position of the straight edge on the stave plank, set the saws to exactly the right position for any width of plank or any desired width of stave 60 to be made from a plank.

It is also to be noted that in this construction a single reciprocating cam or template may operate on all widths of staves by reason of the fact that in wider staves 65 the movement of the saws to cause the form-

ation of the bilge is greater than in narrower staves and the angle of the saws is wider for wider staves than it is for narrower staves. Inasmuch as the shaft 29 and the double crank 33 are rotatable independently 70 of the arm 36, it follows that when the narrower staves are to be made the arms 33 are up and down or more nearly vertical and as a consequence have greater amplitude of movement in a horizontal plane to shift the 75 saws, but when the double crank 33 is turned more nearly into a horizontal plane, the action of the cam or template will give the same oscillation to this double crank and this oscillation will be more nearly vertical 80 and as a consequence the lateral movement of the saws will be less.

The staves are cut out of logs by an ordinary saw mill and are cut into half inch slabs, the first three or four of which have 85 two bark edges. The log is then turned with the sawed portion downward resting on the head blocks. Thus all slabs cut from the rest of this log will have one sawed edge but will have neither bevel nor bulge. The finished stave must have both the bevel and the bulge on each edge of equal form or character. Thus it is necessary to joint both edges 90 of each stave.

The position of the feed table is so nicely 95 adjusted that the left hand saw can remove only enough of the stave to form the bilge, that is the saw only touches the stave at the middle of its length, but by the action of the template, the saw moves inward and removes slightly more and more wood as it moves toward each end. The straight edge is so accurately connected to the right hand saw mandrel support that even a pencil mark drawn on top of the stave along the 100 face of the straight edge will be removed by the right hand saw, and as the operator shifts the saws he imparts simultaneous action to the table 69 and to the straight edge 77 so that the straight edge covers only that 105 portion of the stave which must be removed. Thus no timber is wasted and great capacity 110 of the machine is secured.

I claim:

1. A stave jointer including two saws disposed in planes at all times radial to a common center, manually operable means for adjusting the saws toward or from each other, power operated means for automatically shifting the saws with relation to each other including a reciprocating cam, a cam operating power driven element, and means acting to automatically connect the cam to the power driven element when the stave is about to engage the saws and automatically disconnect the cam from the power driven element when the stave has passed the saws.

2. A stave jointing machine including opposed saw mandrel supports each pivoted at one end upon an axis common to both of 130

the supports, saw mandrels carried upon the supports and carrying saws, the saws being disposed in planes radial to the common axis of rotation of the supports, manually operable means connected to the supports for adjusting the supports toward or from each other, single means for automatically increasing or decreasing the distance between the saws including a template, and a 10 single member operatively engaged with both supports and permitting the independent adjustment of the supports toward or from each other, said member being engaged by said template and acting to automatically shift the saws toward or from each other.

3. A stave jointing machine including opposed saw mandrel supports, each pivoted at one end upon a pivotal axis common to both of the supports, saw mandrels carried 20 thereby and having saws at their confronting ends, the saws being disposed in planes radial to the common axis of oscillation for the supports, a manually oscillatable rock shaft, a double-armed lever mounted upon the rock shaft, links connecting each arm of the lever to one of said supports whereby upon an oscillation of the rock shaft the supports will be shifted toward or from each other, a power operated cam, an arm loosely 30 mounted upon the rock shaft and engaging said cam, and means for rigidly engaging the arm with the rock shaft, said means being manually releasable.

4. A stave jointing machine including opposed saw mandrel supports, each pivoted at its lower end upon a common axis of oscillation, saw mandrels carried thereby, the confronting ends of the saw mandrels carrying circular saws, the saws being disposed in 40 planes radial to the common axis of rotation, a rock shaft, a double-armed lever on the rock shaft, links connecting the extremities of the arms with the respective mandrel supports, a lever on the rock shaft whereby 45 it may be manually shifted to adjust the supports toward or from each other, a power operated cam, an arm loosely mounted upon the rock shaft and operatively engaged by said cam, and means whereby said arm may 50 be connected to the rock shaft to oscillate the same or disconnected therefrom.

5. A stave jointing machine including opposed saw mandrel supports, each pivoted at its lower end upon a common axis of oscillation, saw mandrels carried thereby, the confronting ends of the saw mandrels carrying circular saws, the saws being disposed in planes radial to the common axis of rotation, a rock shaft, a double-armed lever on 60 the rock shaft, links connecting the extremities of the arms with the respective mandrel supports, a lever on the rock shaft whereby it may be manually shifted to adjust the supports toward or from each other, a power operated cam, an arm loosely mounted upon 65

the rock shaft and operatively engaged by said cam, means whereby said arm may be connected to the rock shaft to oscillate the same or disconnected therefrom including a hand grip mounted upon said operating lever, and a clutch for operatively engaging the rock shaft to the arm and operated from said hand grip. 70

6. A stave jointing machine including opposed saw mandrel supports pivotally mounted upon a common axis of oscillation, saw mandrels carried thereby, saws carried on the mandrels and disposed in planes radial to the common center of oscillation, means for automatically shifting the supports toward or from each other including a longitudinally reciprocatable template operatively engaged with the saw supports, a constantly operating power driven element associated with the template, and means acting automatically upon the approach of a stave to the saws to operatively connect the element to said template and upon the recession of the stave from the saws to release the engagement between the element and the template. 75 80 85

7. A stave jointing machine including opposed saw mandrel supports pivotally mounted upon a common axis of oscillation, saw mandrels carried thereby, saws carried on the mandrels and disposed in planes radial to the common axis of oscillation, means for automatically shifting the supports toward or from each other including a longitudinally reciprocatable cam operatively engaged with the saw supports, a constantly operating power driven element associated with the cam, means acting automatically upon the approach of a stave to the saws to operatively connect the element to said cam and upon the recession of the stave from the saws to release the engagement between the element and the cam including a shaft 95

operatively connected to the cam, a ratchet wheel loose on the shaft, a pawl carried by the shaft and normally out of engagement with the ratchet wheel but urged into engagement therewith, and a trip disposed in the path of movement of the stave and having one end disposed slightly in advance of the saws and adapted to be engaged by the stave as it nears the saws, and a latch normally engaging the pawl and holding it from engagement with the ratchet wheel, said trip when engaged by the stave operating to release said latch. 100 105 110 115

8. A stave jointing machine including opposed saw mandrel supports, each mounted for movement toward or from each other, saw mandrels carried thereby and having saws at their confronting ends, a manually oscillatable rock shaft, a double armed lever mounted upon the rock shaft, links connecting each arm of the lever to one of said supports whereby upon an oscillation of the 120 125 130

rock shaft the supports will be shifted toward or from each other, a single power operated cam, an arm loosely mounted upon the rock shaft and engaging said cam, and means for rigidly engaging the arm with the rock shaft in any adjusted position of the rock shaft within range of its oscillation, said means being manually releasable.

9. In a sawing machine, two saw supports pivoted on a common axial line, saws carried on the supports, means for shifting the saws toward and from each other including a shaft, a two armed crank mounted on the shaft, the arms being disposed in diametrically opposite positions and each arm being operatively connected to one of the saw supports, manually operable means for oscillating said shaft, and automatic operating means for oscillating the shaft to cause a predetermined lateral movement of the saws, the shaft being rotatively adjustable by said manual means independently of the automatically operated means.

10. In a sawing machine, two saw supports pivoted on a common axial line, saws carried on the supports and disposed in planes at all times radial to said axial line, means for shifting the saws toward and from each other including a shaft, a two armed crank mounted on the shaft and having its arms disposed in diametrical relation and each arm being operatively connected to one of the saw supports, manually operable means for oscillating said shaft, a cam for automatically oscillating the shaft to cause a predetermined oscillation of the shaft and movement of the saws, and means for operatively connecting said cam to the shaft in any adjustment of the shaft.

11. In a sawing machine, two saw supports pivoted on a common axial line, saws carried on the supports and disposed in planes at all times radial to said axial line, means for shifting the saws toward and from each other including a shaft, a two-armed crank mounted on the shaft and having its arms disposed in diametrical relation and each arm being operatively connected to one of the saw supports, manually operable means for oscillating said shaft, a cam for automatically oscillating the shaft to cause a predetermined oscillation of the shaft and movement of the saws, means for operatively connecting said cam to the shaft in any adjustment of the shaft including a cam operated arm loose on the shaft, and means whereby the arm may be clutched to the shaft in any rotatively adjusted position of the shaft.

12. A stave jointer including two saws disposed in planes at all times radial to a common axis, a feed table disposed in advance of the saws and shiftable laterally, a straight edge movable vertically toward or from the feed table and laterally with relation thereto, means operatively connecting the feed table with one of said saw supports and operatively connecting the straight edge with the other of said saw supports whereby the saw supports and the feed table and straight edge shall be shifted coincidentally, and including means for shifting the straight edge vertically toward or from the feed table.

13. A stave jointing machine including opposed saw mandrel supports pivotally mounted at their lower ends upon a common center, saw mandrels carried thereby and carrying saws, the saws being disposed in planes radial to the common center, a laterally shiftable feed table carrying a guide, a laterally shiftable straight edge coacting therewith, manually operable means for simultaneously shifting both of said supports toward or from each other, means operatively connecting the straight edge and the feed table to said manually operable means to secure the movement in opposite directions of the feed table and straight edge coincidently with the movement of the saw mandrels, and manually operable means for raising or lowering the straight edge out of or into operative relation to the feed table.

14. A stave jointing machine including opposed saw mandrel supports pivoted at their lower ends upon a common center, mandrels carried on the supports, the confronting ends of the mandrels having saws disposed in planes radial to the common center of oscillation, a laterally shiftable feed table, a straight edge coacting therewith and laterally shiftable and vertically movable, a rock shaft operatively engaged with the mandrel supports to coincidently shift them toward or from each other as the rock shaft is oscillated in one or the other direction, a lever whereby the shaft may be oscillated, means operatively connecting the feed table to one of said saw supports and the straight edge to the other of the saw supports whereby the feed table and straight edge shall move coincidently with the mandrel supports, and means mounted upon said lever whereby the straight edge may be raised or lowered.

15. A stave jointing machine including opposed saw mandrel supports pivoted at their lower ends upon a common center, mandrels carried on the supports, the confronting ends of the mandrels having saws disposed in planes radial to the common center of oscillation, a laterally shiftable feed table, a straight edge coacting therewith and laterally shiftable and vertically movable, a rock shaft operatively engaged with the mandrel supports to coincidently shift them toward or from each other as the rock shaft is oscillated in one or the other direction, a lever whereby the shaft may be

130

oscillated, means operatively connecting the feed table to one of said saw supports and the straight edge to the other of the saw supports whereby the feed table and straight edge shall move coincidently with the mandrel supports, cam driving means therefor, means acting to automatically connect the cam with the driving means as a stave approaches the saws and automatically disconnect the cam from the driving means when the stave recedes from the saws, a member operated by the cam, means whereby the rock shaft may be clutched to said cam operated member, said means permitting the rock shaft to be manually adjusted, and manually operable means mounted upon said lever for releasing the clutch and simultaneously lowering the straight edge onto the feed table or engaging the clutch and simultaneously lifting the straight edge from the feed table.

16. In a stave jointing machine, opposed

saw mandrel supports pivotally mounted at their lower ends on a common center, mandrels carried thereby and carrying circular saws at their confronting ends, the saws being disposed in planes at all times radial to the center of oscillation of the mandrel supports, means for shifting the saws toward or from each other including a rock shaft having a double-armed lever mounted thereon, links connecting the mandrel supports with the extremities of said lever, the rock shaft being adapted to be shifted from a position where the lever is vertical to a position where the lever is horizontal, a power operated cam adapted to automatically shift the rock shaft, and manually operable means for shifting the rock shaft independently of the cam.

In testimony whereof I hereunto affix my signature.

WALTER S. MINOR.
